UNITED STATES PATENT OFFICE.

WILLIAM G. PETERS, OF PEORIA, ILLINOIS, ASSIGNOR TO CHARLES A. BERGSTEN, OF PEORIA, ILLINOIS, AND B. E. BRAMBLE, OF CHICAGO, ILLINOIS.

ACCOUNTING SYSTEM.

Application filed June 12, 1925. Serial No. 36,606.

To all whom it may concern:

Be it known that I, WILLIAM G. PETERS, a citizen of the United States, and residing at Peoria, Illinois, have invented the new and useful Improvement in Accounting Systems, of which the following is a specification.

This invention relates to accounting systems and apparatus for carrying out the same, and more particularly to printing and registering devices therefor.

In certain kinds of accounting it frequently happens that bills or similar records must be made out in large numbers. In such cases it is often true that among such a large number there are a great many duplicates. There may, in fact, be so many sheets requiring entries, that it will be convenient to sort the sheets, placing all those requiring the same entries together and then making the entries on each such group separately. In accounting systems of this kind it is often convenient to have a series of rubber stamps, each stamp representing a certain charge or similar class of account, so that the entries may be made accurately and rapidly by stamping. These stamps may bear not only an original charge but also a discount and the net charge, so that a plurality of entries may be made simultaneously. The type are arranged on the stamps so as to register with the rulings of the sheets upon which the entries are to be made so that each item may be stamped in its own column according to such ruling.

Where such groups of identical accounts occur it is often convenient to total such accounts by simply counting the number of sheets of each class and then simply multiplying that number by the amount of the bill stamped thereon. Such counting may be done very conveniently by means of automatic registers on the various stamps arranged to be operated upon performance of the stamping operation.

One of the objects of this invention, therefore, is to provide means by which a sheet may be stamped quickly and accurately and in the proper place on the sheet, and whereby a record of the number of sheets stamped may be made automatically by simply performing the stamping operation.

Another object is to provide improved

means for guiding the stamp during the stamping operation.

In carrying out such a system it frequently happens that several identical entries must be made on the same sheet. Such entries may, of course, be made by simply repeating the stamping operation after shifting the sheet. In such a case, however, it is not desirable that the recording or registering operation be repeated with every stamping operation.

Another object of this invention, therefore, is to provide such a stamping device in which repeated stamping operations may be performed but in which registration thereof will take place only at one of these operations.

Further objects will appear from the following description taken in connection with the accompanying drawing in which:

Figure 1 is a perspective view of a stamping device embodying this invention;

Figure 2 is a sectional view showing the registering mechanism in a position for registering;

Figure 3 is a similar view showing the position of this mechanism after the registering operation; and

Figure 4 is a fragmentary view of the stamped sheet.

Referring to the accompanying drawing 1 designates a base upon which the sheet 2 to be stamped may be placed. The base 1 may be provided with a rail 3 and an index 4 for positioning the sheet. The sheet is simply placed with its left hand edge against the rail 3 and the index 4 registering with some appropriate ruled line on the sheet. The ruling of the sheet is so arranged that with such adjustment the stamped entry will come in the proper columns.

Mounted on the base 1 and outside of the rail 3 is a bracket 5 to which is pivoted at 6 an arm 7. Mounted between the bracket 5 and the arm 7 is a compression spring 8 retained in place by suitable lugs 9 on the bracket and the arm. At the end of the arm 7 there is arranged a socket 10, tapering in form, and adapted to receive and guide a stamp 11 provided with suitable type 12.

Mounted on the stamp 11 and providing a manipulative handle therefor is an auto-

matic register or counter 13. The counter 13 may be provided with flanges 14 overhanging the edges of the stamp 11 and adapted to rest upon the rim of the socket 10 when the stamp is placed therein. These flanges serve to keep the stamp from passing clear through the socket.

Pivoted at 15 on the arm 7 is a rocker plate 16 provided with a cam shaped edge 17, adapted for engagement with the base 1 or the sheet thereon so as to rock the plate 16 when the arm 7 is depressed to bring the stamp down upon the sheet. The plate 16 is provided at its upper end with an operating finger 18 which normally stands to the right, Figure 2, of a downwardly projecting arm of the star wheel 19 which forms part of the counter 13. Pivoted at 20 on the plate 16 is a latch plate 21. The finger 18 projects through a slot 22 in the upper part of the arm 7 and is movable along said slot for operating the counter. The latch plate 21 is provided with an extension 23 which projects in front of the finger 18 and has a shoulder 24 which normally stands before the end of the slot 22 so as to prevent movement of the finger 18. The plate 21 is provided with a weighted tail 25 adapted to maintain the plate in normal position as shown in Figure 2.

In the operation of this device, after properly placing the sheet 2, the stamp 11 is inserted in the socket 10. When the operator presses downwardly upon the counter 13 the downwardly extending arm of the star wheel 19 bears against the extension 23 so as to rock the plate 21 on its pivot 20. This disengages the shoulder 24 from the end of the slot 22 so as to permit movement 40 of the finger 18. Further pressure upon the counter will now rock the arm 7 upon its pivot 6 so as to bring the stamp down upon the sheet. During this movement the cam edge 17 of the plate 16 engages the sheet 45 or the base and causes the plate 16 to rock on its pivot 15, thereby swinging the finger 18 to the left Figure 2. During this movement the finger 18 engages the arm of the star wheel 19 and turns that wheel so as to 50 register the stamping operation on a suitable dial 26. The parts are now in the position shown in Figure 3, the star wheel having moved one notch. When the pressure on the counter is now released the arm 55 7 will rise to its normal position but the finger 18 is prevented by contact with the downwardly extending arm of the star wheel from returning to its normal position. In other words the finger 18 remains 60 on the left hand side, Figures 2 and 3 of the lower arm of the star wheel. Subsequent stamping operations may now be performed without removing the stamp 11 from the guide 10, and such operations will not 65 be recorded on the dial 26. As soon as the

stamp is disengaged from the socket the finger 18 and the latch 23 are permitted to return to their normal positions under the influence of the weight 25. The device is now ready for another recording operation. 70

It will be seen that this invention provides a convenient mechanism for stamping operations which are to be recorded. The guide holds the stamp clear of the sheet and in such a position that when depressed 75 it will print the entry accurately in the desired place on the sheet. The recording mechanism acts to make a record of the first stamping operation only, subsequent operations not being recorded until the stamp is again disengaged from the guide so as to permit the operating finger to return to its normal position. After such disengagement the same or another stamp may be re-engaged with the device and another operation recorded. 80

It is obvious that various changes may be made in the details of construction without departing from the spirit of this invention; it is to be understood, therefore, that this invention is not to be limited to the specific details shown and described. 90

Having thus described the invention what is claimed is:

1. A device for stamping a sheet, comprising, a stamp, a guide adapted to position said stamp clear of the sheet and to guide the same to stamp the sheet, a register on said stamp, means for operating said stamp to stamp the sheet, and means for operating said register upon stamping the sheet. 95

2. A device for stamping a sheet, comprising, a stamp, a guide adapted to position said stamp and to guide the same for stamping the sheet, a register on said stamp, and means operating said register upon stamping the sheet adapted to prevent re-registration. 100

3. A device for stamping a sheet, comprising, a stamp, a guide adapted to position said stamp and to guide the same for stamping the sheet, a register on said stamp, and means normally set to operate said register upon stamping the sheet adapted to be unset upon operation thereof. 110

4. A device for stamping a sheet, comprising, a stamp, a guide adapted to position said stamp and to guide the same for stamping the sheet, a register on said stamp, and means operating said register upon stamping the sheet adapted to prevent re-registration until said stamp is re-engaged with said guide. 120

5. A device for stamping a sheet, comprising, a stamp, a guide adapted to position said stamp and to guide the same for stamping the sheet, a register on said stamp, and means normally set to operate said register upon stamping the sheet adapted to be 130

unset upon operation thereof and to be reset upon dis-engagement of said stamp with said guide.

6. A device for stamping a sheet, comprising, a stamp, a guide adapted to position said stamp and to guide the same for stamping the sheet, a register on said stamp, and means operating said register upon stamping the sheet including an operating finger and a catch controlling said finger adapted to be released upon engagement of said stamp with said guide.

7. A device for stamping a sheet, comprising a stamp, a guide adapted to position said stamp and to guide the same for stamping the sheet, a register on said stamp, and means operating said register upon stamping the sheet including an operating finger and a catch controlling said finger adapted to be released by said register.

8. A device for stamping a sheet, comprising, a stamp, a guide adapted to position said stamp and to guide the same for stamping the sheet, a register on said stamp, and means operating said register upon stamping the sheet including an operating finger adapted upon engagement with the sheet to operate said register, and a catch controlling said finger.

30 9. A device for stamping a sheet, comprising, a stamp, a guide adapted to position said stamp and to guide the same for stamping the sheet, a register on said stamp, and means operating said register upon

stamping the sheet including an operating finger adapted upon engagement with the sheet to operate said register and a catch controlling said finger adapted to be released upon engagement with the sheet to operate said register.

10. A device of the character described, comprising, a guide, means for mounting said guide for movement towards the surface to be stamped, and a stamp adapted to be positioned by said guide.

11. A device of the character described, comprising, a guide, means for mounting said guide for movement towards the surface to be stamped, a stamp adapted to be positioned by said guide and a register on said stamp adapted for actuation upon movement of said guide.

12. A device of the character described, comprising, a guide, a stamp adapted to be positioned by said guide, a register on said stamp adapted for actuation upon positioning of said stamp, and means for preventing reactuation of said register.

13. A device of the character described, comprising, a guide, a stamp adapted to be positioned by said guide, a register on said stamp adapted for actuation upon positioning of said stamp, and means for preventing reactuation of said register until said stamp is again repositioned.

In testimony whereof I affix my signature this 26th day of May, 1925.

WILLIAM G. PETERS.
